Term of patent 14 years

U.S. Cl. D9—151

Int. Cl. D9—01

Fig. 4

FIGURE 1 is a elevation of a bottle showing our new design, the opposite side being the same in appearance;

We claim:

The ornamental design for a bottle, as shown and described.
